SETTEE

Hans Netzer, New York, N. Y.

Application June 28, 1952, Serial No. 20,399

Term of patent 3½ years

(Cl. D15—11)

To all whom it may concern:

Be it known that I, Hans Netzer, a citizen of the United States of America, residing in New York city, county of New York, and State of New York, have invented a new, original, and ornamental Design for a Settee, of which the following is a specification, reference being had to the accompanying drawing, forming part thereof, wherein,

The figure on the drawing is a front perspective view of a settee showing my new design.

The rear of the settee is substantially plain.

I claim:

The ornamental design for a settee, substantially as shown and described.

HANS NETZER.
